UNITED STATES PATENT OFFICE.

GERALD DEAKIN, OF ANTWERP, BELGIUM, ASSIGNOR TO WESTERN ELECTRIC COMPANY, INCORPORATED, OF NEW YORK, N. Y., A CORPORATION OF NEW YORK.

TELEPHONE-CALL DISTRIBUTION SYSTEM.

Application filed November 29, 1922. Serial No. 603,923.

To all whom it may concern:

Be it known that I, GERALD DEAKIN, a citizen of the United States, residing at Antwerp, Belgium, have invented certain new and useful Improvements in Telephone-Call Distribution Systems, of which the following is a full, clear, concise, and exact description.

This invention relates to machine call distributing systems and more particularly to an improved and simplified arrangement of circuits and apparatus whereby a calling line is extended to a connecting circuit over a plurality of automatically operating line finder switches.

The principal feature of the invention resides in the employment of a single test relay in the circuit of the first line finder switch and more particularly to the use of a single relay in association with a first line finder switch wherein such relay performs the combined function of testing for and stopping the brushes on the calling line terminals and holding the calling line busy when necessary, this as shown, being accomplished both under control of the line relay and under control of the second line finder circuit.

Another feature of the invention is that the cut-off relay before operation provides a low resistance path for the second line finder test circuit which is increased when said cut-off relay operates thereby reducing current consumption.

Another feature of the invention resides in such an organization of circuits that double tests at the first line finder are taken care of at the second line finder, thereby simplifying the apparatus used at the first line finder as such double tests under those conditions are not objectionable.

The operation of the circuit of the invention will be understood from the following description when read in connection with the drawing which represents a subscriber's line circuit, a first line finder circuit and so much of the second line finder circuit as is necessary for a clear understanding of the invention. For a complete disclosure of a system to which the present invention is applicable reference is made to U. S. Patent No. 1,482,618 to L. Polinkowsky et al, granted February 25, 1924.

When the subscriber S removes his receiver a circuit is established for the line re-

lay 1 from grounded battery, winding of relay 1, right inner back contact of cut-off relay 2 over the subscriber's line, the substation apparatus and to ground at the left back contact of relay 2. The line relay 1 operates in this circuit and closes its front contacts thereby putting potential on the test terminal 16 from grounded battery, left armature and front contact of relay 1 and resistance 24 in series with the test terminal. 60 A potential is also placed on line terminal 15 from grounded battery, through one winding of relay 2 in parallel with a non-inductive resistance 25 and right front contact of relay 1. 65

Also when line relay 1 closed its front contacts a circuit for the common starting relay 3 was established from grounded battery, left armature and front contact of relay 1 and the winding of relay 3 to ground. 70 Power magnet 4 is now energized to start the brushes hunting for the calling line in a circuit from grounded battery, winding of magnet 4, outer left-hand back contact of test relay 6, lower contact of busy jack 5 75 and left-hand front contact of relay 3 to ground. The first line finder to reach the calling line has its test relay 6 energized in a circuit from ground, high resistance winding 26 of the relay, upper contact of the busy jack 5, test terminal 16 of the calling line, resistance 24, front contact and left armature of relay 1 to battery and ground thereby opening the circuit for the power magnet 4 at the left-hand back contact of relay 6. 80 The power magnet 4 is deenergized and the brushes come to rest on the calling line. Test relay 6 in operating also shunts its high resistance winding 26 by a low resistance winding 27 over a circuit from ground, winding of common starting relay 7 and right-hand front contact of relay 6 and its left-hand winding 27, thus lowering the potential on the test terminal 16 and making the calling line busy to other hunting 85 finders. 90

When the circuit through relay 7 was closed this relay energized and closed at its front contact a circuit for the energization of group line relay 8 through sequence switch contact 21 in position 1. Relay 8 operated and closed a circuit at its front contact for the energization of power magnet 9 from grounded battery, coil of magnet 9 and back contact of group test relay 10. 105 110

The brushes of the second line finder now start hunting for the first line finder which is connected with the calling line and the one whose brushes first reach its terminals 5 establishes a circuit for the energization of group test relay 10 from ground, sequence switch contact 22 in position 1, right-hand high resistance winding of relay 10, sequence switch contact 20 in position 1, terminal 19 of the first line finder, right-hand winding of relay 6 in parallel with a non-inductive resistance 28, terminal 15 of the calling line, right-hand armature and contact of relay 1, left-hand winding of relay 15 2 in parallel with non-inductive resistance 25 to grounded battery. Group test relay 10 energizes in this circuit and opens at its back contact the circuit for power magnet 9 at which the brushes come to rest on the 20 terminals of the first line finder connected to the calling line. Test relay 10 in making its front contact shunts its right-hand high resistance winding by its left-hand low resistance winding, thus lowering the potential 25 at the terminal 19 and making it busy for all other hunting second line finders. Cut-off relay 2 also energizes in this circuit and first closes its right-hand front contact 11 and immediately thereafter disconnects 30 at its right back contact 12 the line relay 1 from the line. The reason for causing contact 11 to make before 12 breaks is to prevent the opening of the above traced circuit and the consequent deenergization of relay 35 6, when relay 1 deenergizes. When the contact 11 of relay 2 was closed a circuit was prepared for the transfer of the above test relay circuit through both windings of relay 2 in series which circuit being of greater 40 resistance due to the addition of the extra relay winding is effective on the release of relay 1 to reduce the holding current. The removal of potential from terminal 16 by the release of relay 1 causes the deenergization 45 and release of relay 7 but relay 6 remains energized by virtue of its right-hand winding which is contained in the test circuit before traced. When relay 10 energized, as above described, a circuit was also closed 50 from battery, through the power magnet of sequence switch 30, front contact of relay 10, front contact of relay 8 to ground, in which circuit the magnet operated to advance the sequence switch out of position 55 1. When the sequence switch leaves position 3, the circuit above traced through the group test relay 10 is broken at sequence switch contact 20, but cut-off relay 2 is maintained energized in circuits (not shown) 60 over other contacts of sequence switch cam 31 throughout the maintenance of the connection.

It will be noted that while the energization of test relay 6 makes the calling line 65 busy to other hunting line finders it does

not prevent double connections due to simultaneous testing. These are purposely permitted as in this way it is not necessary to have closely marginal relays in the first line finder circuit, such double tests at the 70 first line finder being easily cared for by the second line finder circuit in the following manner.

Assume that two first line finders simultaneously pick up the calling line. In the 75 ordinary course of events one of these will be picked up by a second line finder before the other in which case the energization of relay 2 and the consequent release of relay 1 will release the test relay 6 connected to 80 the other first line finder as its high resistance right-hand winding is still open due to the fact that a second line finder has not yet contacted with its terminal 19 to supply ground to complete the holding circuit for 85 the test relay.

Further, let us assume a more remote case in which a double test occurs at both the first and second line finders, that is to say, when two first line finders simultaneously 90 stop on a calling line and then two second line finders simultaneously stop on these two first line finders. In this case one or both of the group test relays 10 of the second line finders thus stopped will be deenergized 95 when the sequence switch contact 22 opens by the switch moving out of position 1, for the reason that the potential of terminal 19 is lowered to such a degree by the opening of the high resistance right-hand winding of relay 10 that two properly adjusted marginal relays will not hold in the circuit. This sequence of events will continue until one second line finder contacts with a busy 100 first line finder in advance of the others. 105

What is claimed is:

1. In a telephone system, a telephone line, a line finder switch for extending said line, a relay associated with said line finder switch arranged to respond to a test indicating the arrival of said line finder on the terminals of said line, and means under the direct control of said relay for thereupon stopping the movement of said line finder and for thereafter marking said line as 110 busy.

2. In a telephone system, a telephone line having a line relay and a cut-off relay, a first line finder switch for extending said line, a second line finder switch for further extending said line, a relay associated with said first line finder switch arranged to respond to a test indicating the arrival of said first line finder on the terminals of said line, and means under the direct control of said relay for thereupon stopping the movement of said first line finder and thereafter marking said line as busy, said line relay having means to control said test relay to maintain said busy indication. 130

3. In a telephone system, a telephone line having a line relay and a cut-off relay, a first line finder switch for extending said line, a second line finder switch for further extending said line, a relay associated with said first line finder switch arranged to respond to a test indicating the arrival of said first line finder on the terminals of said line, and means controlled by said relay for thereupon stopping the movement of said first line finder and thereafter marking said line as busy, said line relay having means to control said test relay to maintain said busy indication until said second line finder 10 has further extended said line, and means in said second line finder for energizing said cut-off relay.

4. In a telephone system, a telephone line having a line relay and a cut-off relay, a first line finder switch for extending said line, a second line finder switch for further extending said line, a relay associated with said first line finder switch arranged to respond to a test indicating the arrival of 20 said first line finder on the terminals of said line, and means controlled by said relay for thereupon stopping the movement of said first line finder and thereafter marking said line as busy, said line relay having means to control said test relay to maintain said busy indication until said second line finder has further extended said line and means in said second line finder for energizing said cut-off relay and thereafter controlling said test relay to maintain said busy indication.

5. In a telephone system, a telephone line having a line relay and a cut-off relay, a first line finder switch for extending said line, a second line finder switch for further extending said line, a relay associated with said first line finder switch arranged to respond to a test indicating the arrival of said first line finder on the terminals of said line, and means controlled by said relay for thereupon stopping the movement of said first line finder and thereafter marking said line as busy, said line relay having means to control said test relay to maintain said busy indication until said second line finder 40 has further extended said line and means in said second line finder for energizing said cut-off relay, said cut-off relay having means for increasing the resistance of its own circuit so as to decrease the current drain in this circuit during the maintenance of a connection.

6. In a telephone system, a telephone line having a line relay and a cut-off relay, a first line finder switch for extending said line, a second line finder switch for further extending said line, a relay associated with said first line finder switch arranged to respond to a test indicating the arrival of said first line finder on the terminals of said line, and means controlled by said relay for

thereupon stopping the movement of said first line finder and thereafter marking said line as busy, said line relay having means to control said test relay to maintain said busy indication until said second line finder has further extended said line and means in said second line finder for energizing said cut-off relay and thereafter controlling said test relay to maintain said busy indication, 70 said cut-off relay having means for increasing the resistance of its own circuit so as to decrease the current drain in this circuit during the maintenance of a connection.

7. In a telephone system, a telephone line having a line relay and a cut-off relay, a first line finder switch for extending said line, a second line finder switch for further extending said line, a relay associated with said first line finder switch arranged to respond to a test indicating the arrival of said first line finder on the terminals of said line, and means controlled by said relay for thereupon stopping the movement of said first line finder and thereafter marking said line as busy, said line relay having means to control said test relay to maintain said busy indication until said second line finder has further extended said line, means in said second line finder for energizing said cut-off relay and thereafter controlling said test relay to maintain said busy indication, said cut-off relay having means for increasing the resistance of its own circuit so as to decrease the current drain in this circuit during the maintenance of a connection, to prevent another second line finder from stopping on the line extended by said first line finder.

8. In a telephone system, a telephone line appearing in the terminals of a plurality of line finders, means responsive to the initiation of a call on said line for starting a plurality of said line finders, means responsive to the simultaneous finding of said line by a plurality of said finders for stopping said finders on said line, means under control of each of said finders for starting a plurality of secondary finders in search of said first finders which have stopped on said line, and means responsive to the simultaneous finding of a plurality of said first finders by a plurality of said secondary finders for preventing any one of said last mentioned secondary finders from remaining on the terminals of any one of said first finders.

9. In a telephone system, a telephone line appearing in the terminals of a plurality of line finders, means responsive to the initiation of a call on said line for starting a plurality of said line finders, means responsive to the simultaneous finding of said line by a plurality of said finders for stopping said finders on said line, means under control of each of said finders for starting a plurality of secondary finders in search of said first finders which have stopped on said line,

means responsive to the simultaneous finding of a plurality of said first finders by a plurality of said secondary finders for preventing any one of said last mentioned secondary finders from remaining on the terminals of any one of said first finders, and means responsive to the finding of one of said first finders by one of said secondary

finders for releasing all but the one said first finder on the terminals of which said secondary finder has stopped. 10

In witness whereof, I hereunto subscribe my name this 10th day of November A. D., 1922.

GERALD DEAKIN.
